UNITED STATES PATENT OFFICE

WILLIAM WARD DAVIDSON, OF EVANSTON, ILLINOIS, ASSIGNEE TO DAVIDSON MANUFACTURING COMPANY, OF MADISON, WISCONSIN, A CORPORATION OF WISCONSIN

BLANK SEPARATING AND FEEDING MACHINE

Application filed June 12, 1931. Serial No. 543,864.

This invention relates to blank separating machines of the type in which withdrawal of blanks, one at a time, from a pack is effected by a friction roller, commonly known as 5 friction feeders.

One object of the invention is to provide a feeder of the type specified which is simple in construction, effective in operation, relatively inexpensive to manufacture, and which may quickly and conveniently be adjusted to adapt it for feeding blanks which differ in thickness, stiffness, smoothness and as regards other characteristics which may affect separation thereof.

A further object of the invention is to provide a blank separating device which may either be built into or constructed as a separate unit and attached bodily to and operationally connected with what may be designated 10 a primary blank-handling machine so that it will be driven directly therefrom and will also deliver separated blanks directly to the feed devices of said primary machine, and to synchronize the operation of said separator mechanism with the feed devices of said primary machine.

To effect the objects thereof, a blank separating mechanism embodying my invention and improvements, comprises the various features, combinations of features and details of construction hereinafter described and claimed.

In the accompanying drawings, in which the invention is fully illustrated,

Figure 1 is a side view of a blank separating machine embodying my invention and improvements, shown as applied in use to a known commercial printing machine.

Figure 2 is a top plan view thereof.

Figure 3 is an enlarged, fragmentary, sectional elevation on the line 3—3 of Fig. 2.

Figure 4 is a fragmentary side elevation, partly in section, showing the blank receptacle in tilted position.

Figure 5 is a fragmentary, sectional elevation showing certain devices, as in Fig. 3, but in different operative positions.

Figure 6 is a detached, fragmentary top plan view, partly in section, of the feeding devices of the machine to which my improved

blank separating machine is shown as applied; and

Figure 7 is a sectional elevation on the line 7—7 of Fig. 6.

Describing the invention with reference to the drawings, I will first describe my improved separator mechanism and will then describe its adaptation for feeding blanks to a primary machine to which it is applied in use.

The frame of my improved blank separator mechanism designated as a whole A, comprises a frame member 1 which is adapted to be secured to the frame of a primary machine to which the separator mechanism is to be applied in operation, indicated as a whole B, rigidly secured to which are plates 2, 2', which are secured to the frame member 1 by screws 3.

The pack of blanks to be fed or separated, designated C, is supported in a suitable receptacle designated as a whole D, mounted between the frame plates 2, 2', and which comprises side frame members 4, 4', which are connected adjacent their front and rear ends by rods 5, 5' forming what may be designated the frame of the receptacle, the rod 5 rigidly connecting said members 4, 4', and the rod 5' for reasons presently apparent, being rotatable in bearings formed therein. The receptacle D is supported so as to be bodily movable vertically, by means of arms 6, 6', an end of each of which is pinned or otherwise secured to a shaft 7 rotatably mounted in bearings formed in arms 8 which depend from opposite ends of the frame member 1, and the outer ends of which, respectively, are pivotally connected to the side frames 4, 4', of the receptacle adjacent their lower ends, said receptacle being guided in its vertical movements by roller studs 9 secured therein, which engage slots 10 formed in the side members 2, 2', of the main frame of the separator mechanism.

In operation, the pack receptacle D is maintained yieldingly at the limit of its vertical movement—which, as presently explained, is defined by contact of the top of the pack of blanks C in the receptacle D, with the separator roll—by means of a coil spring 11, oppo-

site to the direction of movement of the receptacle D, and which is secured to the frame member 1.

Figure 3 shows the receptacle D in its lower position, the roller studs 9 being in contact with the top of the pack of blanks C, and the coil spring 11 being compressed.

Figure 4 shows the receptacle D in its upper position, the roller studs 9 being disengaged from the top of the pack of blanks C, and the coil spring 11 being extended.

Figure 5 shows the receptacle D in its intermediate position, the roller studs 9 being disengaged from the top of the pack of blanks C, and the coil spring 11 being partially extended.

Figure 6 shows the feeding devices of the machine to which my improved

site ends of which are attached to pins 12, 12', secured, respectively, in the supporting arm 6' and in the side plate 2' of the separator frame.

10 The pack receptacle D also comprises angle plates 13, 13' having vertically and horizontally disposed flanges, the horizontal flanges extending inwardly towards each other and forming the support on which the pack of blanks C rests directly. As shown, also, said angle plates are supported so as to be adjustable towards and from each other, thus providing for varying the width of the space between the vertical flanges of said angle plates 15 to receive blanks of different widths. In what I now consider the preferable construction, said angle plates are thus adjustably supported by means of brackets 14 secured to their undersides and which are provided with 20 bearings adapted to receive the rod 5 with only slight clearance, thus rendering said angle plates both slidably and rotatably adjustable on said rod. As shown, also, said angle plates are adapted to be secured in adjusted positions on the rod 5 by means of set screws 15 threaded through the bearings of the brackets 14 in position to engage said rod.

25 As shown, the means for supporting said angle plates 13, 13', also comprises a rod 16, the ends of which are secured to lever arms 17, 17', pinned or otherwise rigidly secured to the rod 5' which, as previously stated, is rotatably mounted in bearings in the side plates 4, 4' of the blank receptacle and serves to connect the same, said rod 16 being slidably fitted to guides 18 formed between the undersides of the angle plates 13, 13', and plates 19 secured to said angle plates and supported in spaced relation thereto.

30 In accordance with my invention, and for reasons presently explained, the angle plates 13, 13' are adapted to be adjusted pivotally on the rod 5 to vary the inclination of said angle plates. As shown, the means for this purpose consists of a screw 20, preferably a thumb screw, the shank of which is mounted to turn in a hole formed in a stud 21 pivoted to the side plate 4 of the blank receptacle D adjacent its rear end, and adapted to be secured therein against turning movement, in positions corresponding to desired angular adjustment of said angle plates by lock nuts 22 threaded to said screw below the stud 21, said screw also having threaded engagement 35 with a hole formed in a stud 23 pivoted to a lever arm 24 secured to the rod 5' so as to turn therewith and which, as shown, is secured to or formed integral with the arm 17 which supports the rod 16.

40 To reduce the duty on the spring 11, thus providing for the use of a lighter spring, the side members 4, 4' of the blank receptacle may be skeletoned or cut away, as shown, to an extent consistent with adequate strength, and 45 the weight of the receptacle D and, if desired,

a portion of the weight of the pack C contained therein, may be supported by a suitable counter balance applied to the shaft 7, consisting of a bar 25 an end of which is secured to said shaft so as to turn therewith, the free end of which projects frontwards and secured to which, so as to be adjustable lengthwise thereof, is a counter weight 26, which is adapted to be secured in any desired adjustment on said bar by a set screw 27.

50 In accordance with my invention, the means for separating and withdrawing blanks from the pack C contained in the blank receptacle D, one at a time, consists of a separator plate 28 and feed roll 29. As regards their usual features and, excepting as herein-after particularly described and pointed out, said separator plate and roll are old and well known and their construction and operation will readily be understood from an examination of the drawings by persons skilled in the art, without a description thereof in detail.

55 As shown, the separator plate 28 is secured in fixed position to the frame member 1, with the surface thereof against which the front ends or edges of the blanks rest, continuous with the side or face of the frame member 1 to which it is secured, and the feed roll 29 is supported so as to be adjustable towards and from said separator plate, means being provided for effecting such adjustment and for securing said separator roll in adjusted positions. As shown, the feed roll shaft 30 is rotatably mounted in the free ends of arms 31, pinned or otherwise secured to a shaft 32 rotatably mounted in bearings in the side plates 2, 2' of the separator frame, the relation being such that pivotal movement of said arms in opposite direction will impart movement to the feed roll 29 towards and from the separator plate 28. Pivotal movement to effect such adjustment is adapted to be imparted to the arms 31 by means of a screw 33 secured in a stud 34 pivoted to an arm 31 at a distance from the axis of the shaft 32, the threaded end of which extends through a hole formed in a swivel stud 35 pivoted to the side plate 2 of the separator frame and threaded to which at opposite sides of said stud are nuts 36, preferably thumb nuts, by means of which adjustment of the roll 29 relative to the separator plate 28 can readily be effected, as will be understood.

60 Due to the manner of supporting the angle plates 13, 13', by which the pack of blanks C is supported directly, and also to the adjustability of the feed roll 29 towards and from the separator plate 28, said separator mechanism may quickly and conveniently be adapted for feeding blanks of different kinds, as blanks varying in thickness, stiffness and finish, the angle plates 13, 13' being adjusted towards the horizontal and the feed roll 29 away from the separator plate 28, as shown in Fig. 3, when feeding heavier, stiffer

and rougher blanks, and said plates being adjusted away from the horizontal and the feed roll 29 towards the separator plate 28, as shown in Fig. 4, when feeding or separating 5 thinner, more flexible and smoother blanks.

In operation, intermittent rotation in a direction to withdraw blanks from the pack C supported in the receptacle D is adapted to be imparted to the feed roll 29 by suitable operating connection with a driven part of the primary machine B to which the separator unit is applied, as shown with the main shaft 3 of thereof. As shown, said means comprises a rack bar 37 secured in fixed position to a link 10 38, the front end of which is pivotally connected to the lower end of a lever arm 39 pivoted to the side frame of the machine B at 40 and to which oscillation in one direction is adapted to be imparted by means of a cam 41 secured to the shaft b acting in co-operation with a roller stud 42 on the lever arm 39 and which is adapted to be moved in the opposite direction by means of a spring 43 applied thereto. 15 The rack bar link 37 is supported and guided by means of a slot 44 formed lengthwise therein which is slidably fitted to the projecting end of a stub shaft 45 rotatably mounted in a bearing in the proximate lever arm 31 20 and to which the feed roll shaft 30 is operatively connected. 25

Intermittent rotary movement is imparted to the stub shaft 45 and thus to the feed roll shaft 30 in operation, by means of a pinion 46 mounted on said stub shaft in position to engage the rack 37, said pinion operatively engaging said stub shaft by means of a suitable ratchet gear 47, the relation being such that rotation of the gear 46 corresponding to 30 turning movement of the lever arm 39 by the cam 41 will turn the feed roll 29 in a direction to withdraw blanks from the pack C.

While my invention contemplates the use 35 of any suitable or desired form of ratchet gear, a ratchet gear which I now consider preferable for the purpose, is fully shown and described in U. S. Letters Patent No. 1,627,015, dated May 3, 1927, to which reference is here made.

With the described construction, it is obvious that the feed roll 29 will be actuated to withdraw a blank from the pack C in the receptacle D at each revolution of the shaft b of the machine B.

As shown in the drawings, see particularly Figs. 3, 5, 7 and 8, the primary machine B is particularly designed and adapted to be hand fed, the blank feeding devices comprising pull-out rolls 48 and 49, of which the roll 48 is rotatable on a fixed axis and the roll 49 is rotatably mounted at the ends of arms 50 which project frontwards from a frame member 51 pivotally supported by 40 studs 52 secured in the side frames of the

machine and which is adapted to be turned pivotally at intervals to depress the roller 49 into contact with the roll 48 by means of a roller 53 pivotally mounted at the front end of a plate 54 which is pivotally mounted concentric with the frame member 51 and is connected thereto by means of a bolt 55 which extends through holes formed in a boss 56 formed on the front side of the member 51 and in a lateral projection 57 on the plate 70 54, said member 51 and plate 54 being maintained at the limit of their relative pivotal movement, defined by the bolt 55, by a spring 58 inserted between the projection 57 and a part of the member 51, said spring being 75 a coiled spring and confined in a hole formed in the boss on said member 51, as shown. When free to respond thereto, the member 51 is adapted to be maintained yieldingly in position with the roller 49 above and out 80 of contact with the roller 48 by means of a coiled spring 59, opposite ends of which are attached to the plate 54 and to the adjacent side frame member of the machine B.

Blanks fed to the machine B are delivered upon a skeletonized plate or table 60 and their position relative to the feeding devices of the machine is defined by means of stop fingers 61 which are pivotally supported on lugs 62 formed on the machine frame and are maintained yieldingly in position with their ends projecting above the plate or table 60, contact of the advancing edges of blanks fed to the machine therewith, operating to effect register of the blanks delivered thereto with 90 the feeding devices of the machine.

In the operation of the machine B, also, the stop fingers 61 are adapted to be turned pivotally to depress their free ends below the top of the delivery plate or table 60, substantially simultaneously with contact of the pull-out roller 49 with the roller 48, effected by turning movement of the frame member 51 by the roller 53, as heretofore explained, thus releasing the blanks and permitting 100 them to pass to the printing devices.

As shown, the means for thus depressing the stop fingers 61 consists of a lever arm 63 operatively connected with said stop fingers so as to turn therewith, a pin 64 secured in 110 which, projects into the path of movement of a lateral lug or projection 65 formed on the plate 54, the relation being such that contact of the lugs 65 with the end of the pin 64 as the plate 54 is turned pivotally by contact of the roll 53 with the high portion of the actuating cam, will depress the stop fingers 61 below the level of the receiving plate or table 60.

As my invention relates to mounting a 125 blank separating mechanism or unit in association with a blank-handling machine primarily designed to be hand fed, so as to form, in effect, a constituent part thereof, and feeding blanks withdrawn from a pack C in the 130

receptacle D thereof directly to the feed devices thereof, I attain the object of the invention by providing means for first guiding the advancing edges of blanks with-
 5 drawn from the receptacle D between the spaced apart pull-out rolls 48 and 49 of the machine B and into contact with the stop fingers 61 and in then releasing said blanks to permit them to buckle, as shown in Fig. 5, thus avoiding the necessity for accurately
 10 timing the operation of the separator unit or mechanism and the feed devices of the machine B. As shown, the means for thus guiding and releasing withdrawn blanks con-
 15 sists of fingers 66 secured to a rock shaft 67 mounted to turn in bearings in the side plates 2, 2' of the frame of the separator unit or mechanism, which project frontward over the feed roll 29 and separator plate 28 into
 20 the opening at the front side of the frame of the machine B defined by the converging sides of the member 51 and the blank receiving plate or table 60. In accordance with the invention, oscillating movement is adapt-
 25 ed to be imparted to the shaft 67 to turn the fingers 66 from depressed position, shown in Fig. 4, in which they will serve as guides for the advancing edges of the blanks, to raised position, shown in Fig. 5, in which they
 30 will release fed blanks and permit them to buckle. As shown, the means for imparting oscillating movement to the rock shaft 67 consists of an arm 68 secured thereto, mounted on which is a roller stud 69 which projects
 35 over and rides upon a cam surface on the upper edge of the link 38, comprising relatively low and high sections 70 and 71 connected by an inclined section 72, the relation being such that engagement of the roller stud
 40 with the low section 70 of said cam, will correspond to depressed position of the fingers 66, shown in Fig. 3, and with the high section 71 thereof, corresponding to raised position of said fingers, shown in Fig. 5.
 45 As shown, the fingers 66 are maintained yieldingly depressed by a torsion spring 73 applied thereto, opposite ends of which are attached to the arm 68 and to a fixed member and which surrounds said shaft as a guide.
 50 I claim:
 1. In a blank separating mechanism, the combination of a frame, a vertically movable pack support mounted thereon with the pack supporting surface thereof approximately
 55 horizontal, means for maintaining said pack support yieldingly raised, blank separating means comprising a feed roll mounted above said pack support in position to contact with the uppermost blank of a pack supported
 60 thereon, said feed roll being rotatable on a fixed axis and contact therewith defining fully raised position of the pack, a separator plate supported in association with said feed roll, means for varying the relative inclina-
 65 tion of the pack support and separator plate,
 70 75 80 85 90 95 100 105 110 115 120 125

the pack support raising means being cali-
 brated to provide necessary traction to render the blank separating means operative.

2. In blank separating mechanism, the combination of a frame, a vertically mov-
 70 able pack support mounted thereon with the pack supporting surface thereof approxi-
 mately horizontal, means for maintaining
 said pack support yieldingly raised, blank
 separating means comprising a feed roll
 mounted above said pack support in position
 to contact with the uppermost blank of a
 pack supported thereon, said feed roll being
 rotatable on a fixed axis and contact there-
 with defining fully raised position of the
 pack, a separator plate supported in associa-
 tion with said feed roll, means for varying
 the relative inclination of the pack support
 and separator plate and means for varying
 the distance between the feed roll and said
 separator plate, the pack support raising
 means being calibrated to provide necessary
 traction to render the blank separating means
 operative.

3. In blank separating mechanism, the combination of a frame, a vertically movable pack support mounted thereon with the pack supporting surface thereof approximately horizontal, means for maintaining said pack support yieldingly raised, blank separating means comprising a feed roll mounted above said pack support in position to contact with the uppermost blank of a pack sup-
 90 ported thereon, said feed roll being rotatable on a fixed axis and contact therewith defining fully raised position of the pack, a separator plate supported in association with said feed roll, means for varying the relative inclina-
 95 tion of the pack support and separator plate, and separate means for adjusting the feed roll towards and from the separator plate, the pack support raising means being cali-
 brated to provide necessary traction to render the blank separating means operative.

4. Blank separating mechanism as speci-
 fied in claim 1, the pack support of which
 comprises side frame members, front and
 rear rods which connect said side frame
 members in spaced relation, the rear rod be-
 ing rotatable, a rock shaft, arms secured
 thereto the free ends of which are pivotally
 connected to opposite side frames of said
 pack support, means for guiding said pack
 support vertically, said pack support also
 comprising a pack receptacle pivoted to the
 front rod connecting the side frames of the
 pack support, and means for flexibly connect-
 ing said receptacle with the rear supporting
 rod of the frame of the pack support provid-
 ing means for turning said receptacle pivot-
 ally to vary its inclination.

5. Blank separating mechanism as speci-
 fied in claim 1, the pack support of which
 comprises side frame members, front and
 rear rods which connect said side frame
 120 125 130

members in spaced relation, the rear rod being rotatable, a rock shaft, arms secured thereto the free ends of which are pivotally connected to opposite side frames of said pack support, means for guiding said pack support vertically, said pack support also comprising a pack receptacle pivoted to the front rod connecting the side frames of the pack support, and said receptacle with the rear supporting rod of the frame of the pack support providing means for turning said receptacle pivotally to vary its inclination, comprising lever crank arms secured to the rear rod which connects the side frames of the pack support, and a rod supported by said arms on which said pack rests directly.

6. Blank separating mechanism as specified in claim 1, the pack support of which comprises side frame members, front and rear rods which connect said side frame members in spaced relation, the rear rod being rotatable, a rock shaft, arms secured thereto the free ends of which are pivotally connected to opposite side frames of said pack support, means for guiding said pack support vertically, said pack support also comprising a pack receptacle pivoted to the front rod connecting the side frames of the pack support, and means flexibly connecting said receptacle with the rear supporting rod of the frame of the pack support providing means for turning said receptacle pivotally to vary its inclination, comprising crank arms secured to the rear rod for connecting the side frames of the pack support, a rod supported by said arms on which said pack receptacle rests directly, and means for turning said rear rod pivotally and for securing it in adjusted positions.

40 7. In blank separating mechanism, the combination of a frame a vertically movable pack support mounted thereon with the pack supporting surface thereof approximately horizontal, means for maintaining said pack support yieldingly raised, blank separating means comprising a feed roll mounted above said pack support in position to contact with the uppermost blank of a pack supported thereon, said feed roll being rotatable on a fixed axis and contact therewith defining fully raised position of the pack, a fixed separator plate supported in association with said feed roll, and means for varying the inclination of the pack support.

55 8. Blank separating mechanism as specified in claim 2, in which the means for supporting the feed roll comprises a rock shaft, arms secured thereto provided with bearings for said feed roll, and means for turning said rock shaft and arms pivotally and for securing them in adjusted positions.

9. Blank separating mechanism as specified in claim 2, in which the means for supporting the feed roll and for varying the distance between said feed roll and separator

plate, comprises a rock shaft, arms secured thereto provided with bearings for said feed roll, and means for turning said rock shaft and arms pivotally and for securing them in adjusted positions, comprising a screw pivoted to a feed roll supporting arm, a stud mounted on the separator frame provided with a hole through which said screw extends, and nuts threaded to said screw at opposite sides of said stud and adapted to be clamped upon the same.

10. In combination, a primary blank handling machine equipped with stop fingers arranged to effect register of blanks delivered thereto with the feeding devices of said machine, a blank separating and feeding mechanism mounted in association with said primary machine and arranged to deliver separated blanks directly thereto, and means operating initially to guide the advancing edges of separated blanks into contact with the stop fingers of said primary machine and to permit buckling thereof while being fed, when their advancing edges contact with the stop fingers of said primary machine.

11. In combination, a primary blank handling machine equipped with stop fingers arranged to effect register of blanks delivered thereto with the feeding devices of said machine, a blank separating mechanism mounted in association with said primary machine and arranged to deliver separated blanks directly thereto, and means operating initially to guide the advancing edges of separated blanks into contact with the stop fingers of said primary machine and to then release said blanks to permit buckling thereof.

12. The structure specified in claim 11, the blank guiding and releasing means of which comprises pivoted fingers, means for maintaining said fingers depressed in position to guide blanks into contact with the stop fingers of the primary machine, and means for raising said guide fingers to release said blanks and permit buckling thereof.

13. The structure specified in claim 11, the blank guiding and releasing means of which comprises pivoted fingers, means for maintaining said fingers depressed in position to guide blanks into contact with the stop fingers of the primary machine and means operatively connected with an actuated part of said primary machine for raising said guide fingers to release said blanks.

14. The structure specified in claim 11, the blank guiding and releasing means of which comprises a rock shaft, fingers secured thereto, means for maintaining said rock shaft in position corresponding to depression of said guide fingers, and means to turn said shaft to elevate said guide fingers, comprising a cam bar, means for supporting and guiding the same, means for imparting reciprocating movement thereto, and arms secured to said

rock shaft and a roller stud mounted thereon positioned to operativey engage the cam surface of said cam bar.

15. The structure specified in claim 10, the blank guiding means of which comprises pivoted fingers the weight of which is proportioned to permit buckling of the blanks while bearing the weight of said fingers, when their advancing edges contact with the 10 stop fingers of the primary machine.

In witness that I claim the foregoing as my invention, I affix my signature this 9th day of June, 1931.

WILLIAM WARD DAVIDSON.
